UNITED STATES PATENT OFFICE

2,597,027

PRODUCTION OF NITROPARAFFINS

Herbert J. Passino, Englewood, and Louis C. Rubin, West Caldwell, N. J., assignors to The M. W. Kellogg Company, Jersey City, N. J., a corporation of Delaware

Application March 27, 1947, Serial No. 737,666

8 Claims. (Cl. 260—644)

1

This invention relates to improvements in the manufacture of nitrogen derivatives of carbon compounds and relates more particularly to improvements in the manufacture of nitrogen derivatives of hydrocarbons. Still more particularly the invention relates to improvements in the manufacture of nitrogen derivatives of paraffin hydrocarbons by nitrating these hydrocarbons with the reaction product obtained from the catalytic oxidation of ammonia.

Heretofore in the synthesis of aliphatic nitro-compounds by direct vapor-phase nitration of paraffin hydrocarbons with nitric acid, deterioration of construction materials in the nitric acid vaporization zone has presented important economic obstacles because of severe corrosion problems arising from the reaction of the nitric acid upon costly equipment. In order to overcome the corrosive effect of the acid, utilization of highly expensive corrosion-resistant material has heretofore been necessary when the aforementioned nitration technique is practiced.

It is therefore an object of the present invention to provide for an improved process for the manufacture of nitrogen derivatives of paraffin hydrocarbons.

A further object of this invention is to provide an improved process for the direct manufacture of nitrogen derivatives of paraffin hydrocarbons, by nitrating these hydrocarbons with the reaction product obtained from the catalytic oxidation of ammonia.

Other objects and advantages inherent in the invention will be apparent from the following more detailed disclosure.

In accordance with the process of this invention, these objects are accomplished, in general, by a method of nitration which comprises the steps of charging ammonia and an oxidizing gas into a reaction system over a suitable catalyst under controlled conditions of temperature, pressure, and reaction time to generate nitric acid and/or some quantities of oxides of nitrogen in the presence of introduced paraffins or paraffin derivatives, immediately reacting these paraffins with the synthesized nitric acid and/or nitrogen oxides at a temperature slightly below the cracking temperature of the paraffins to form corresponding nitroso-paraffins, subjecting these nitroso-paraffins to further oxidation with an oxidizing gas to form the corresponding nitro-paraffins, and separating nitro-paraffins thus obtained from resulting gaseous products.

The details, including additional features and advantages of the process of the invention, will

be understood by those skilled in the art from the accompanying drawing which illustrates diagrammatically one form of the apparatus employed and capable of carrying out one embodiment of the process of our invention. While the invention will be described in detail by reference to one embodiment of the process employing the apparatus illustrated in the drawing, it should be noted that it is not intended that the invention be limited to the embodiment as illustrated, but is capable of other embodiments which may extend beyond the scope of the apparatus illustrated in the drawing. Some of the mechanical elements, which form no part of the invention but are necessary to effect the transfer of liquids and vapors and to maintain the conditions of temperature and pressure necessary to carry out the function of the apparatus, are omitted in order to simplify the description.

10 It will be understood, however, that much equipment of this nature is necessary and will be supplied by those skilled in the art.

Referring to the drawing, ammonia and an oxidizing gas, such as air, oxygen, or oxygen-enriched air are introduced, respectively, through valved charging-lines 10 and 11 to a reaction system. This reaction system is illustrated diagrammatically in the drawing by reaction tower 12, which comprises a suitable reaction vessel having a mixing and preheating zone and a series of reaction zones, the functions of which will be hereinafter described in accordance with the process of the invention. The ammonia and oxidizing gas, thus introduced into tower 12, are first passed into a mixing and preheating zone A. 25 In zone A the charging stock thus introduced through lines 10 and 11 is mixed, and preferably heated rapidly to a temperature sufficiently high to maintain the proper operating conditions of temperature and pressure in reaction zone B as hereinafter described and into which the mixed and preheated charging stock is next transferred.

The mixed charging stock of ammonia and an oxidizing gas, thus introduced into reaction zone B, is passed over a suitable catalytic material under conditions of temperature, pressure, and reaction time effective to convert by oxidation a substantial proportion of the ammonia to nitric acid in the vapor state. We have found that such oxidation is most efficiently carried out by operating reaction zone B at a temperature with approximately the range of 800° C. to 1000° C. and at a super-atmospheric pressure from about 10 to about 15 atmospheres. Accordingly,

55

as indicated above, the charging stock in zone A should preferably be preheated sufficiently high to maintain the catalyst mass within the aforementioned temperature range, to effect necessary oxidation without the application of external energy.

The catalytic material employed in the oxidation reaction in zone B may be a solid material in a fluid-bed or fixed-bed state. While we have found that alloys of platinum may be overall suitable when used as catalysts in the aforementioned oxidation reaction, other catalysts may be effectively employed; for example, we may use such catalysts as iron, cobalt, nickel or their oxides. It is also possible to use such catalysts as oxides of manganese and magnesium; dioxides of manganese and zirconium; and vanadium pentoxide. In addition other catalysts may be used where such catalysts comprise thoria and rare earth oxides; cobaltic oxide and either bismuth trioxide, aluminum oxide or beryllium oxide; manganese dioxide and calcium oxide; and silica gel and chromic oxide.

As described above, the mixed charging stock of preheated ammonia and oxidizing gas is passed over the catalyst under conditions of temperature and pressure within the aforementioned ranges, for a time sufficient to oxidize substantial proportions of ammonia to nitric acid in the vapor state. The product of the reaction thus produced in zone B and comprising substantial quantities of nitric acid, and/or some quantities of oxides of nitrogen is passed to a reaction zone C where it is immediately contacted with a preheated gaseous stream of the paraffin hydrocarbon or a mixture of paraffin hydrocarbons to be nitrated. Paraffins which are thus to be nitrated, are introduced into zone C through valved line 13. These preheated gaseous paraffins or paraffin mixtures are introduced into zone C through line 13 in such proportions that the temperature in this zone is maintained slightly below the cracking temperature of the introduced paraffins. The immediate contact of the synthesized nitric acid, and/or nitrogen oxides obtained as the reaction product from zone B in the process described above, with the introduced paraffins in zone C results in the formation of the corresponding nitroso-paraffins in this zone as a gaseous reaction product, by reason of the intermediate reaction of nitric acid, and/or nitrogen oxides in the vapor form produced from their reaction with the introduced paraffins. It will be noted that the immediate reaction of the nitric acid with paraffins in zone C, following the above-mentioned acid synthesis, results in the prevention of the corrosive effect of the acid upon equipment.

The gaseous reaction products produced in zone C and comprising substantially corresponding nitroso-paraffins of the introduced paraffins, as described above, are passed to a reaction zone D. The temperature of the products thus introduced into zone D is next reduced to a temperature suitable for further oxidation to form corresponding nitro-paraffins. To effect such reduction in temperature, the products introduced into zone D are first passed through a heat exchange medium, illustrated diagrammatically in the drawing by heat exchanger 14. Nitroso-paraffins present in the reaction product thus reduced in temperature, are next subjected to further oxidation in zone D by admixture with an oxidizing gas, such as air, oxygen, or oxygen-enriched air to form a reaction product, com-

prising substantially the corresponding nitro-paraffins of the paraffins introduced into zone C through line 13. The oxidizing gas thus employed is introduced into zone D through valved line 15. The reaction product thus produced is withdrawn from zone D through valved line 16.

As described above, the reaction product withdrawn from zone D through line 16, comprises substantially nitro-paraffins. In addition there may also be present unreacted paraffins and other gaseous products wherein the latter may comprise one or more unabsorbed gases. For example, where air or oxygen-enriched air is used as the oxidizing gas introduced into the reaction system through line 11 and/or line 15, in the process described above, unabsorbed gases thus obtained may comprise a mixture consisting largely of nitrogen, carbon dioxide, and other gases normally present in the air. The reaction product thus withdrawn from zone D is next transferred through line 16 to an intermediate point in a fractionation tower 17. Tower 17 is operated under conditions of temperature and pressure effective to separate the higher boiling nitro-paraffins from unreacted paraffins and gaseous products present in the reaction product introduced into tower 17 through line 16. Separated nitro-paraffins are next withdrawn through valved line 18 for further use outside the scope of the present process. The aforementioned gaseous products are distilled overhead from tower 17 and withdrawn through valved line 19 for further use or treatment outside the scope of the present process. Unreacted paraffins present in the aforementioned reaction product obtained from zone D, are withdrawn from tower 17 at an intermediate point through valved line 20 which is at a point above the inlet of line 16 into the tower. These paraffins may be next recycled through valved line 21 into line 13, with which line 21 connects, for further use in tower 12 in the process described above.

In certain instances, depending upon properties of the paraffins introduced into zone C through line 13, oxidation of corresponding nitroso-paraffins in zone D may of necessity be conducted at such low temperatures as to prevent direct fractionation of the nitro-paraffin thus produced. For example, when the reaction temperatures in zone D are at or near the boiling point of unreacted paraffins, it will be necessary to add additional heat in order to obtain the desired fraction and reflux conditions in tower 17. The necessity for this preheating or reheating is dependent upon the quantities of the paraffins fed into tower 12 through line 13. In such cases, the temperature of the reaction product obtained from zone D may be raised sufficiently high to permit subsequent direct fractionation of nitro-paraffins from unreacted paraffins and gaseous products in tower 17 in the process described above. Conveniently, this may be accomplished by transferring the aforementioned reaction product withdrawn from zone D through line 16, via valved line 22, through any conventional heating device illustrated diagrammatically in the drawing by heat exchanger 23. The reaction product thus heated to a temperature sufficiently high to permit subsequent fractionation of nitro-paraffins from other components contained therein, is transferred from heat exchanger 23 through line 24 into line 16, with which line 24 connects, and is subjected to subsequent fractionation in tower 17 in the process described above.

It will be noted that the aforementioned reaction system, illustrated diagrammatically in the drawing by tower 12, comprises a series of mixing, preheating, and reaction zones in a single vessel for carrying out the process of the invention, as described. However, where so desired, it is possible to carry out the process of the invention in a series of suitable vessels, rather than a single vessel, each of such vessels being adapted to maintain the same function as the corresponding mixing, preheating, or reaction zones illustrated in the drawing by the zones in tower 12.

Although our invention has been described with particular reference to a process for the manufacture of nitrogen derivatives of paraffin hydrocarbons, as shown above, it should be noted that it is not restricted to the nitration of open-chain paraffins. The process of the invention may be also similarly applied in the manufacture of nitrogen derivatives of cyclo-paraffins to produce corresponding cyclo-nitro-paraffins; similarly nitro-benzenes may be produced from benzene or benzene derivatives; nitro-toluene from toluene or its derivatives; and nitro-cyclopentane and nitro-cyclohexane from cyclopentane and cyclohexane respectively. In each instance the degree of nitration (mono-, di-, or tri-) substitution will depend upon the severity of operating conditions. In addition, while we have described a particular embodiment of our invention for purposes of illustration, it should be understood that various modifications and adaptations thereof which will be obvious to one skilled in the art may be made within the spirit of the invention as set forth in the appended claims.

Having thus described our invention, what we claim and desire to secure by Letters Patent is:

1. The process of manufacturing nitrogen derivatives from paraffin hydrocarbons which comprises the steps of passing ammonia and an oxidizing gas through a heating zone at a temperature between about 800° C. and about 1000° C. and at a pressure between about 10 and about 15 atmospheres in the presence of a catalytic material for a reaction time effective to convert a substantial proportion of the ammonia to nitric acid in the vapor state, contacting the vapors thus produced immediately upon formation with at least one gaseous paraffin hydrocarbon at a temperature slightly below the cracking temperature of said paraffin hydrocarbon to form the corresponding nitroso-paraffin and in an amount in excess of that required to effect substantially complete consumption of nitric acid thus formed, subjecting said nitroso-paraffin to further oxidation at a reduced temperature with an additional quantity of said oxidizing gas to form the corresponding nitro-paraffin, and recovering said nitro-paraffin.

2. The process of manufacturing nitrogen derivatives from paraffin hydrocarbons which comprises the steps of passing ammonia and an oxidizing gas through a heating zone at a temperature between about 800° C. and about 1000° C. and at a pressure between about 10 and about 15 atmospheres in the presence of a catalytic material for a reaction time effective to convert a substantial proportion of the ammonia to nitrogen oxides in the vapor state, contacting the vapors thus produced immediately upon formation with at least one gaseous paraffin hydrocarbon at a temperature slightly below the cracking temperature of said paraffin hydrocarbon to form the corresponding nitroso-paraffin and in an amount in excess of that required to effect

substantially complete consumption of nitrogen oxides thus formed, subjecting said nitroso-paraffin to further oxidation at a reduced temperature with an additional quantity of said oxidizing gas to form the corresponding nitro-paraffin.

3. The process as defined by claim 2 in which said oxidizing gas comprises essentially free oxygen.

10 4. The process as defined by claim 2 in which said oxidizing gas comprises air.

5. The process as defined by claim 2 in which said oxidizing gas comprises oxygen-enriched air.

15 6. The process of manufacturing nitrogen derivatives from paraffin hydrocarbons which comprises the steps of passing ammonia and an oxidizing gas through a heating zone at a temperature between about 800° C. and about 1000° C. and at a pressure between about 10 and about 15 atmospheres in the presence of a catalytic material for a reaction time effective to convert a substantial proportion of the ammonia to nitric oxide in the vapor state, and contacting the vapors thus produced immediately upon formation with at least one gaseous paraffin hydrocarbon at a temperature slightly below the cracking temperature of said paraffin hydrocarbon to form the corresponding nitroso-paraffin and in an amount in excess of that required to effect substantially complete consumption of nitric oxide thus formed, subjecting said nitroso-paraffin to further oxidation at a reduced temperature with an additional quantity of said oxidizing gas to form the corresponding nitro-paraffin, and recovering said nitro-paraffin.

20 7. The process of manufacturing nitrogen derivatives from paraffin hydrocarbons which comprises the steps of preheating a charging stock comprising ammonia and an oxidizing gas to a temperature between about 800° C. and about 1000° C. and at a pressure between about 10 and about 15 atmospheres, passing said preheated charging stock into a first reaction zone in contact with a catalyst comprising platinum for a time effective to convert a substantial proportion of the ammonia to nitric oxide in the vapor state, passing the vapors thus produced into a second reaction zone, contacting said vapors in said second reaction zone with a gaseous paraffin hydrocarbon at a temperature

25 slightly below the cracking temperature of said paraffin hydrocarbon to form the corresponding nitroso-paraffin and in an amount in excess of that required to effect substantially complete consumption of nitric oxide thus formed, passing

30 55 the nitroso-paraffin thus formed and unreacted paraffin hydrocarbon into a third reaction zone, subjecting said nitroso-paraffin in said third reaction zone to further oxidation at a reduced temperature with an additional quantity of said oxidizing gas to form the corresponding nitro-paraffin, and removing said nitro-paraffin from said third reaction zone.

60 8. The process of manufacturing nitrogen derivatives from paraffin hydrocarbons which comprises the steps of preheating a charging stock comprising ammonia and an oxidizing gas to a temperature between about 800° C. and about 1000° C. and at a pressure between about 10 and about 15 atmospheres, passing said preheated

65 70 charging stock into a first reaction zone in contact with a catalyst comprising platinum for a time effective to convert a substantial proportion of the ammonia to nitric oxide in the vapor state, passing the vapors thus produced into a second reaction zone, contacting said vapors in

75

said second reaction zone with a gaseous paraffin hydrocarbon at a temperature slightly below the cracking temperature of said paraffin hydrocarbon to form the corresponding nitroso-paraffin and in an amount in excess of that required to effect substantially complete consumption of nitric oxide thus formed, passing the nitroso-paraffin thus formed and unreacted paraffin hydrocarbon into a third reaction zone, subjecting said nitroso-paraffin in said third reaction zone to further oxidation at a reduced temperature with an additional quantity of said oxidizing gas to form the corresponding nitro-paraffin, separating said nitro-paraffin from unreacted paraffin hydrocarbon, and returning unreacted paraffin hydrocarbon to said second reaction zone. 15
